RADIO PHONOGRAPH CABINET

Robert Davol Budlong, Skokie, Ill., assignor to
Zenith Radio Corporation, a corporation of Illinois

Application January 17, 1951, Serial No. 13,846

Term of patent 3½ years

(Cl. D56—4)

To all whom it may concern:

Be it known that I, Robert Davol Budlong, a citizen of the United States, residing at Skokie, in the county of Cook, State of Illinois, have invented a new, original, and ornamental Design for a Radio Phonograph Cabinet, of which the following is a specification, reference being made to the accompanying drawing, forming a part thereof.

Figure 1 is a front elevational view of the radio phonograph cabinet with the lid closed, showing the new design;

Figure 2 is a side elevational view of the cabinet with the lid closed;

Figure 3 is a top plan view thereof;

Figure 4 is a side elevational view of the new cabinet with the lid open;

Figure 5 is a cross-section taken along line 5—5 in Figure 1; and

Figure 6 is a cross-section taken along line 6—6 in Figure 1.

The rear of the cabinet is plain and the side not shown is identical with the side shown.

I claim:

The ornamental design for a radio phonograph cabinet, as shown and described.

ROBERT DAVOL BUDLONG.
